(57) **CLAIM**

The ornamental design for a display screen of an electronic device with a graphical user interface as shown and described.

DESCRIPTION

FIG. 1 is a top view of a display screen of an electronic device with a graphical user interface, showing a first embodiment of our new design. The base portion includes the display screen with a touch pad and function keys as the graphical user interface.

FIG. 2 is a perspective view of the design shown in FIG. 1 in another environment.

FIG. 3 is a top view of a display screen of an electronic device with a graphical user interface, showing a second embodiment of our new design. The base portion includes the display screen with a touch pad and function keys as the graphical user interface; and,

FIG. 4 is a perspective view of the design shown in FIG. 3 in another environment.

The features shown in evenly spaced broken lines showing a display screen of an electronic device with a graphical user interface are included for the purposes of showing portions of the article, which form no part of the claimed design. The dash-dot line represents a truncation of the electronic device and form no part of the claimed design.
